(57) **CLAIM**

The ornamental design for a mixer, as shown and described.

DESCRIPTION

FIG. 1 is a front, left and top perspective view of a mixer showing our new design;

FIG. 2 is a rear, right and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the mixer in accordance with our new design illustrating a state in which an environmental structure (a mixing paddle) is attached to the mixer.

The broken lines in the drawings illustrate the environmental structures or portions of the mixer which form no part of the claimed design.
